UNITED STATES PATENT OFFICE.

JOHN GUSTAF SJOBERG, OF OAKLAND, CALIFORNIA.

CLAMP.

No. 797,465.

Specification of Letters Patent.

Patented Aug. 15, 1905.

Application filed November 8, 1904. Serial No. 231,924.

To all whom it may concern:

Be it known that I, JOHN GUSTAF SJOBERG, a citizen of the United States, residing at Oakland, in the county of Alameda and State of California, have invented new and useful Improvements in Clamps, of which the following is a specification.

My invention relates to clamps; and its primary object is to provide a new and useful device of this character adapted to be used to secure the hatch-covers used upon ships carrying oil and other liquids in such positive closed position that all leakage is prevented.

A further object of the invention is to provide a clamp which can be easily and cheaply manufactured, which is simple of construction, and which is composed of few parts, so arranged and constructed as not to be liable to become broken or inoperative.

A still further object of the invention is to provide a clamp which when not in use may be thrown in such position as not to interfere with the turning of the hatch upon its hinges to clear the hatch-opening.

The invention consists in the construction, combination, and arrangement of parts hereinafter fully described, claimed, and illustrated in the accompanying drawings, which show the preferred form of my invention, and wherein—

Figure 1 is a sectional view through a portion of the deck of a vessel, hatch-coaming, and hatch-cover, showing the application of my improved clamp in position to secure the hatch-cover in applied position against leakage. Fig. 2 is a rear elevation thereof, and Fig. 3 a top plan view.

Referring to the drawings by reference-numerals, 1 designates the deck of a vessel provided with the usual hatch-opening, about which is secured the hatch-coaming 2. Pivotally secured to the coaming 2 is a hatch-cover 3, which is provided on its under surface with a strengthening-bar 4, recessed, as shown at 5, for the reception of a gasket 6, adapted to engage the upper edge of the coaming 2. The edges of the hatch-cover 3 project laterally beyond the coaming 2, and to provide for the reception of a portion of the clamp to permit of its application said lateral edges are provided with recesses 7.

My improved clamp comprises three elements—a base or bracket 8, a link 9, pivotally secured to said bracket, and an actuating arm or lever 10, eccentrically and pivotally secured to the upper end of said link 9. The

base or bracket 8 comprises a horizontally-disposed portion adapted to be secured to the upper surface of the deck by means of bolts and nuts 11 or their equivalent and ears 12, rising vertically from said horizontally-disposed portion and arranged in parallelism. The ears 12 are provided with alining openings for the reception of a pivot-pin 13, which passes through the lower end of the link 9 to pivotally secure the same to the base or bracket 8. The actuating arm or lever 10 is provided with a head 14 bifurcated for the reception of the upper end of the link 9, to which the actuating arm or lever is eccentrically pivoted by means of a pivot-pin 15. This manner of connecting the actuating arm or lever 10 to the link 9 provides a cam-head which is provided with cam-faces 16, which are adapted to be brought into engagement with the upper surface of the hatch-cover 3 to securely force the latter down into closed position to prevent all liability of any leakage between the gasket 6 and the hatch-coaming 2.

It will be understood that as many of these clamps are to be used as is found necessary. The base or bracket 8 is preferably secured to the deck of a vessel directly under the recess 7, so as to permit the link 9 to be moved into the recess to place the cam-heads 14 upon the upper surface of the hatch-cover 3. When the cam-head is thus disposed, the actuating arm or lever 10 is turned upon its pivot-pin to bring the cam-faces 16 into engagement with the upper surface of the hatch-cover 3, which causes the hatch-cover to be forced downward upon the upper edge of the coaming 2 with such positiveness that all liability of leakage is obviated. In order to assist the turning of the actuating arm or lever 10 either to lock the hatch-cover or to remove the clamp, said arm or lever is provided with a socket 17, into which a lever may be inserted. When it is desired to remove the clamps to permit the hatch-cover to be swung upon its hinges, the actuating arm or lever 10 is swung in the reverse position upon its pivot-pin, which will move its cam-faces up out of engagement with the hatch-cover, after which the clamp may be swung into the position shown in dotted lines, Fig. 1, in which position it is out of the way and will not interfere with the free operation of the hatch-cover.

From the foregoing description, taken in connection with the accompanying drawings,

the construction and mode of operation of the invention will be understood without a further extended description. Changes in the form, proportions, and minor details of construction may be made within the scope of the invention without departing from the spirit or sacrificing any of the advantages thereof.

Having thus fully described the invention, what is claimed as new is—

In a device of the character described, a hatch-coaming, a hatch-cover, and a clamp

comprising a base, a link pivotally secured thereto, and a cam-head pivotally secured to said link and adapted to engage the hatch-cover, said cam-head being formed with a socket to receive a removable lever substantially as described.

In testimony whereof I affix my signature in presence of two witnesses.

JOHN GUSTAF SJOBERG.
